UNITED STATES PATENT OFFICE.

ALFRED HOPCRAFT, OF NEW YORK, N. Y.

DESIGN FOR AN ADVERTISING-CARD.

SPECIFICATION forming part of Design No. 20,524, dated February 17, 1891.

Application filed January 7, 1891. Serial No. 377,036. Term of patent 3½ years.

To all whom it may concern:

Be it known that I, ALFRED HOPCRAFT, a citizen of the United States, residing at the city of New York, in the county of New York 5 and State of New York, have invented and produced an original Design for Advertising-Cards, of which the following is a specification, reference being had to the accompanying drawings, forming a part thereof.

10 Figure 1 is a plan view of an advertising-card, showing my new design; and Fig. 2 is a longitudinal sectional elevation of the same.

A represents a card of single thickness and oblong in form, having curved and downwardly-depressed edges *a* *a'* and one curved and downwardly-depressed end edge *b*. At the end opposite to the curve *b* appears an irregular bevel or depression *c*, which terminates in a notch *c'* at one corner. Beyond the said 15 20 irregular depression *c* appear three other de-

pressions, forming a succession of ridges *d* *d'* *d''*. The ridge *d* terminates in an angle *d'*, while the ridges *d'* *d''* terminate in rounded corners *d''*, as clearly shown in the drawings.

What I claim is—

25 The design for a card herein shown and described, the same showing curved downwardly-depressed edges *a*, *a'*, and *b* and at one edge an irregular downwardly-depressed ridge *c*, terminating in notch *c'*, and beyond the ridge 30 *c* a succession of other ridges, substantially as shown.

In testimony that I claim the foregoing as my invention I have signed my name, in presence of two witnesses, this 3d day of January, 35 1891.

ALFRED HOPCRAFT.
